4 Claims. (Cl. 313—68)

1

The invention relates to a device for transmitting or producing electrical oscillations having a wavelength of the order of magnitude of some few decimetres by means of an electric discharge tube comprising at least one cathode, one anode and a secondary-emission electrode in the said order. The invention also relates to a discharge tube for use in such a device.

It is already known to produce short waves by means of secondary-emission tubes in a so-called tetrode arrangement, in which, viewed from the cathode, the wires of the control-grid and the perforated anode provided to constitute a grid wound on edge are located in succession and in which the plate-shaped secondary-emission electrode surrounds the assembly. The results thus obtained are highly satisfactory in the wavelength range from 3 to 1, by reason of the small divergence in the transit times of the primary and the secondary electrons. With shorter waves, however, the results are rapidly impaired, since shadow grids of the required small dimensions can be realized with difficulty only and in addition part of the primary electrons is always directly intercepted by the anode.

It is also known to produce short waves with the aid of a cavity resonator tube, in which the elongated cathode faces a slit in an elongated resonant cavity, the edges of which form the anode, whilst the rear wall of the resonant cavity is secondarily emitting and in which, on account of the different voltages across anode and secondary-emission electrode, the face and the rear of the resonant cavity are not coupled galvanically, but only capacitatively. The primary electrons are bunched by a magnetic field extending in their direction of movement. Although this involves a slight transit time divergence for the primary electrons, the effect of the magnetic field is comparatively unfavourable in that it prevents the secondary electrons from being rapidly intercepted by the anode and thus results in undue space charge and transit time divergence.

The said disadvantages can be largely obviated by using a device according to the invention.

According to the invention, in a device for transmitting or producing electrical oscillations having a wavelength of the order of magnitude of some few decimetres by means of an electric discharge tube comprising at least one cathode, one perforated anode and one secondary-emission electrode in the said order, the electrons, after leaving the cathode, are bunched electrostatically so as to pass through an aperture in the anode,

2

and the substantially flat secondary-emission electrode which is at right angles to the direction towards the cathode, exhibits a small salient part which is directed towards the cathode and which, according as the system has a symmetry plane or axis, terminates in a sharp ledge or tip, whilst the primary electrons are projected on to the salient part and the area directly adjacent it.

The primary electrons directed towards the centre of the secondary-emission electrode find their way to the sides of the salient part, where the electrical field is very favourably directed for the interception of the secondary electrons by the anode in contradistinction to the field that may be developed in the case of completely flat secondary-emission electrodes. Secondary electrons are thus prevented from returning to the cathode-anode space and hence from being given an excessive transit time. The salient part may protrude to the extent of extending between the parts of the anode, this extent, however, not exceeding half the thickness. Only if this condition is fulfilled, the concentration of the primary electrons on the secondary-emission electrode does not vary with the voltage across the latter and, even in the case of extensive control of the secondary-emission electrode the secondary electrons are effectively intercepted. Accordingly these tubes permit of working with a voltage across the secondary-emission electrode which is only a fraction of the anode voltage; it is true that in this case the oscillations produced are greatly distorted, but this is not inconvenient in the case of coupling to a resonant cavity.

In order that the invention may be more clearly understood and readily carried into effect, it will now be described with reference to the accompanying drawing, in which Fig. 1 is a horizontal sectional view of an electric discharge tube according to the invention, which comprises a control-grid, Fig. 2 is a vertical sectional view of an electric discharge tube according to the invention, in which the anode and the secondary-emission electrode are directly sealed in the wall; Fig. 3 is a view, in cross-section, along line 3—3 of Fig. 2, and Fig. 4 is a view, in cross-section, along line 4—4 of Fig. 2.

Referring to Fig. 1, 1 designates a flat cathode which is adapted to emit on two sides. Bridge supporting rods 2 have wound on them the wires 3 of the control-grid, and at the outside of the grid, on either side of the cathode, there are arranged two rods 4 lying in a plane by which the electrons emanating from the cathode are bunched so as to impinge not on the anode constituted by

rods 5, but on the secondary-emission electrode 6 arranged on either side of the cathode, this impingement occurring substantially on the flanks of the protruding ledge 7 and the area directly adjacent it. By reason of the shape of the secondary-emission electrode as shown and the arrangement of the anode the secondary electrons are sucked away by a field which is substantially at right angles to the direction of movement of the primary electrons. Since the tube comprises a control-grid it is adapted to be used not only as a valve oscillator but also as an amplifier. The spacings between the electrodes may be derived from the adjoining scale and the length of the system is approximately 5 mm. At a wavelength of 50 cms. a gain in energy of 70 may be attained at a bandwidth of 2 mc./s.

Referring to Fig. 2, 10 designates the glass wall of the discharge tube, the bottom 11 of which has sealed in it three solid studs for the filament supply and the cathode lead. In front of the flat cathode 13, which emits upwards there is arranged a partly conical bunching screen 16 (the tube exhibits cylinder symmetry) which, together with the cathode, is secured to a mica screen 14. This screen is secured, by means of two glass beads 15 to a planar anode 17. The anode carries a conical screen 18, which projects the bunched primary electrons through an aperture 19 in the anode to the salient tip 21 of the secondary-emission electrode 20. The anode and the secondary-emission electrode are sealed, in the form of flat discs, directly into or onto the glass wall (so-called disc seal); the distance between the flat part of the anode and the secondary-emission electrode is approximately 0.5 mm. On connection of the tube by means of the protruding edges of anode and secondary-emission electrode to a tunable cavity resonator suitable for this purpose, the tube is adapted to oscillate at a wavelength of from 40 to 10 cms. At an anode voltage of 1200 volts and a voltage across the secondary-emission electrode of 100 volts, the current of the secondary-emission electrode is 10 milli-amperes (the secondary-emission electrode has been treated with caesium oxide). The output is 20% at a wavelength of 40 cms. and 10% at a wavelength of 15 cms. Sealed in addition on top of the secondary-emission electrode is a glass wall 22 which permits of cooling the secondary-emission electrode in a simple manner with a sufficient supply of water.

What I claim is:

1. An electron discharge tube comprising a cathode source of electrons, means to form said electrons into a beam, a planar anode having the plane thereof arranged substantially perpendicular to said beam and being provided with an aperture through which said beam passes, and a secondary emissive electrode positioned on the side of said anode remote from said cathode source, said secondary emissive electrode having a salient portion thereof arranged in the path of

said beam and positioned closer to the plane of said anode than the remaining effective portion of said secondary emissive electrode.

2. An electron discharge tube comprising a cathode source of electrons, means to form said electrons into a beam, a planar anode having the plane thereof arranged substantially perpendicular to said beam and being provided with an aperture through which the said beam passes, and a secondary emissive electrode positioned on the side of said anode remote from said cathode source, said secondary emissive electrode having a salient portion thereof arranged in the path of said beam and extending into said aperture whereby said salient portion is positioned closer to the plane of said anode than the remaining effective portion of said secondary emissive electrode.

3. An electron discharge tube comprising a cathode source of electrons, means to form said electrons into a beam, an anode comprising two rod-shaped members spaced apart and arranged in a plane substantially perpendicular to said beam, said spaced rod-shaped members defining an aperture through which said beam passes, a control grid interposed between said cathode and said anode, and a secondary emissive electrode positioned on the side of said anode remote from said cathode source, said secondary emissive electrode having a salient portion thereof arranged in the path of said beam and positioned closer to the plane of said anode than the remaining effective portion of said secondary emissive electrode.

4. An electron discharge tube comprising a cathode source of electrons, means to form said electrons into a beam, a disc shaped planar anode having the plane thereof arranged substantially perpendicular to said beam and being provided with a central aperture through which said beam passes, and a disc shaped secondary emissive electrode positioned on the side of said anode remote from said cathode source, said secondary emissive electrode having a central cup-shaped portion extending towards said anode and a salient portion of said cup-shaped portion arranged in the path of said beam and positioned closer to the plane of said anode than the remaining portions of said cup-shaped portion.
